UNITED STATES PATENT OFFICE.

JOSIAH W. SHERWOOD, OF GREEN LAKE, MICHIGAN, ASSIGNOR OF ONE-HALF TO ELIZA S. SHERWOOD, OF GREEN LAKE, MICHIGAN.

FARM-GATE.

No. 830,181.

Specification of Letters Patent.

Patented Sept. 4, 1906.

Application filed April 28, 1906. Serial No. 314,300.

To all whom it may concern:

Be it known that I, JOSIAH W. SHERWOOD, a citizen of the United States, residing at Green Lake, in the county of Allegan and 5 State of Michigan, have invented certain new and useful Improvements in Farm-Gates, of which the following is a specification.

My invention relates to improvements in farm-gates; and its objects are, first, to provide a means for adjusting the strain upon the wires in a frameless farm-gate and, second, to provide a means of closing and fastening the gate that will not necessitate exact measurements between the supporting-posts. I 15 attain these objects by the mechanism illustrated in the accompanying drawings, in which—

Figure 1 is an elevation of a gate upon its supporting-posts. Fig. 2 is a plan of the 20 lower fastening device. Fig. 3 is a plan of the upper fastening device, and Fig. 4 is an elevation of the back hinge for supporting the upper end of the supporting-bar B'.

Similar letters refer to similar parts 25 throughout the several views.

The gate consists of a series of wires secured at one end to the upright bar B and at the other end to the upright bar B', which latter bar is permanently supported in the 30 boxes G G' on the post A'. The box G is made in two pieces, the piece g being detachable from the portion G, so that the bar may be readily removed at pleasure. The portion g is secured to place by means of a bolt 35 inserted at g' and is so constructed that if the box is one side up it will be supported from turning by the rib h' and if the other side is up or reversed it will be supported by the inclined surface h, the two holding it firmly to 40 place, no matter which side up it may be. The bar B' may be held firmly to place, so that it cannot slide downward, either by means of a key, as b, or by screwing the portion g firmly against it.

45 My appliance for straining and fastening the gate to place consists of an upper box F and a lower box F'. In the lower box I place a horizontal bar D, that passes through the box and is provided with a hole d through 50 one end for the reception of the lower end of the bar B. This horizontal bar is provided with a series of notches d' for the reception of a key d'' and is so arranged that the end of the bar at d may be adjusted to the desired

distance from the post A to properly receive 55 the end of the bar B even though the length of the wires is such that it would be difficult to make them engage without this adjustability.

In the box F, I place a sliding horizontal 60 bar C, having a hook c at one end and provided with small apertures c' through the body at intervals, so that the eccentric E may be secured at different distances from the hook c to correspond with the relative 65 length of the wires H and the distance apart of the posts A A', so that the bar B may be engaged by the hook on the bar C without special regard to the relative distances hereinbefore mentioned. It is designed that the 70 eccentric E shall act upon the edge of the box F, so that a firm substantial bearing is always insured.

The box F' may be so formed that the key will pass through the notches in the bar D 75 back of the box, as in Fig. 1, or through between two portions of the box, as in Fig. 2. The latter is considered the most convenient, as with it there is no danger of the bar sliding back when released from the strain of the 80 gate when it is removed for opening.

The principal object of constructing the box G in two pieces, as hereinbefore described, is to enable me to place the box below the upper strand of wire or between any two 85 strands of wire on the gate and place the box or remove it from around the bar B' without trouble, which could not be done with a solid box like G'.

Having thus fully described my invention, 90 what I claim as new, and desire to secure by Letters Patent of the United States, is—

1. In combination with a frameless gate, a lower box a horizontal bar passing through said box and having a hole through one end 95 and notches in the body, and a key for securing said bar to place; an upper box, a horizontal bar passing through said box and having a hook at one end and holes at intervals through the body of the bar, an eccentric pivoted to said bar through one of said holes and arranged to actuate said bar by action upon the edge of the box, substantially as described and shown.

2. In combination with a frameless gate, 105 supporting-bars connected by longitudinal wires, boxes for permanently securing one of said bars, one of said boxes being divided, a

box and upper sliding bar at the opposite end of the gate, said bar having a hook at one end and holes at intervals in the bar, an eccentric pivoted to said bar in position to engage one of the gate-bars at the upper end, a lower horizontal bar, a supporting-box therefor, said bar having a hole through one end and notches in the body, and a key engaging one of said notches to adjust said bar to the

length of the gate and secure it to place, substantially as and for the purpose set forth.

Signed at Grand Rapids, Michigan, April 6, 1906.

JOSIAH W. SHERWOOD.

In presence of—

I. J. CILLEY,
LOU CILLEY.
